UNITED STATES PATENT OFFICE.

GEORGE HENRY WHEARY, OF RACINE, WISCONSIN.

WARDROBE SEAT-BOX.

1,230,252.

Specification of Letters Patent. Patented June 19, 1917.

Application filed March 13, 1915. Serial No. 14,059.

To all whom it may concern:

Be it known that I, GEORGE HENRY WHEARY, a citizen of the United States, and resident of Racine, in the county of Racine 5 and State of Wisconsin, have invented new and useful Improvements in Wardrobe Seat-Boxes, of which the following is a description, reference being had to the accompanying drawings, which are a part of this specification. 10

This invention relates to improvements in a wardrobe seat box.

Wardrobe seat boxes or chests now on the market are usually of box-like form with 15 hinged top covers to permit access to the interior portion of the box, and the interior portion of the box is usually in the form of one large compartment into which garments are placed in folded position one on top of 20 another. In removing or replacing one of the garments, unless on top, it is necessary to remove all the garments resting on top of the one it is desired to remove to gain access thereto. This requires considerable 25 time and is otherwise objectionable. Furthermore in boxes of this kind with but one compartment no provision is made for separating different articles such as shoes, etc., and consequently it is not desirable to place 30 them in the compartment with the garments.

Folded garments become creased and wrinkled and are otherwise unfit for wear when kept in this manner due to the weight of other garments resting thereon.

35 It is one of the objects of the present invention to overcome the before mentioned objectionable features and provide a wardrobe seat box in which provision is made for keeping articles of wear in separate compartments within the box in such a manner as to preserve their shape without crushing 40 or creasing and to permit their easy removal without disturbing the other articles.

A further object of the invention is to 45 provide a wardrobe seat box having a wardrobe section positioned therein and mounted to be swung to an upright position outside of the box in such a manner as to permit the opening and closing of the box cover and removal of articles from compartments in the 50 lower portion of the trunk.

A further object of the invention is to 55 provide a wardrobe seat box in which the wardrobe section is provided with hanger tracks and extension tracks and garment hangers mounted thereon to permit garments

to be draped thereover without wrinkling or crushing the garments.

A further object of the invention is to provide a wardrobe seat box which is of very 60 simple construction, is strong and durable and is well adapted for the purpose described.

With the above and other objects in view the invention consists of the improved wardrobe seat box and its parts and combinations as set forth in the claims, and all equivalents thereof.

In the accompanying drawings in which the same reference characters indicate the 70 same parts in all of the views:

Figure 1 is a perspective view of the improved wardrobe seat box showing the wardrobe section in vertical position outside of the box and the box cover in closed 75 position;

Fig. 2 is a transverse sectional view thereof with the box cover and the wardrobe section in closed position, the cover being indicated in open position by dotted lines; 80

Fig. 3 is a longitudinal sectional view of the wardrobe seat box, the box cover being shown in open position and the wardrobe section being indicated in open position by dotted lines; and 85

Fig. 4 is a top view of the wardrobe seat box with the box cover in open position.

Referring to the drawings the numeral 5 indicates an enlarged box-like inclosure 90 having side, end and bottom walls 6, 7 and 8 respectively, supporting legs 9 and a hinged top seat cover 10. The end walls 7 rise above the seat portion to form end arms 11 and to give the box an ornate appearance. 95

One of the end walls of the box is divided vertically into two parts and the upper part 12 is free from connection with the side walls and is hinged to the upper edge portion of the lower part by hinges 13 so it may 100 be swung outwardly to horizontal position. This upper hinged end portion or panel preferably forms the end wall of the wardrobe section or tray 14 of the box although the tray may be formed independent of the 105 panel and merely connected thereto. The wardrobe section or tray 14 is of rectangular form and when within the box is provided with end, side and bottom walls and an open top which is covered by the top seat 110 cover 10. The tray is supported within the box on the upper edges of the partitions 15

which divide the lower interior portion of the box into a plurality of compartments 16 for holding various articles of wear. The tray may be tilted upwardly to a vertical position outside of the box and when in this position (as shown in Fig. 1) the seat cover may be swung to open or closed position as the tray is outside of the path of travel of said seat cover. The tray is held and locked in vertical position by brace links 16 which are pivotally connected at their upper ends to the sides of the wardrobe section and at their lower ends have a sliding connection with slotted brace members 17 mounted in the box. The ends of the slotted brace members adjacent the tray are provided with locking recesses 18 into which the projecting portions 19 of the brace links drop when the tray is in vertical position.

10 The seat cover 10 is also provided with a brace link 20 for limiting the swing of said seat cover to open position.

15 The upper portion of the wardrobe section is provided with fixed tracks 21 having extensible tracks 22 hinged to their outer ends which may be swung horizontally out of the tray to positions in horizontal alignment with the fixed tracks so that garment hangers 23 mounted on the tracks may be 20 slid outwardly thereon.

25 Attention is directed to the fact that the wardrobe section is in the form of a tray when within the trunk and is provided with a bottom portion having side and end portions rigidly connected thereto and movable therewith. The lower end portion of the section, when the section is in upright position, serving as a shelf to hold articles of apparel, etc. This shelf portion also serves 30 to protect and hold in place the apparel placed within the section.

35 The bottom portion of the tray serves to support the garments suspended within the tray when the tray is swung to a horizontal 40 position within the box.

Copies of this patent may be obtained for five cents each, by addressing the "Commissioner of Patents, Washington, D. C."

It is to be understood that various changes may be made in the construction and arrangement of the parts without departing from the spirit and scope of the invention.

From the foregoing description it will be 50 seen that the wardrobe seat box forms an ornate article of furniture which is of very simple construction, is strong and durable and is well adapted for holding various articles of wear in proper shape. 55

What I claim as my invention is:

1. A wardrobe seat box, comprising a box-like member having an open top and end portions which project above the seat portion of the member, one of said end portions formed of two hinged together parts, a seat cover hinged to the box-like member and movable to closed position between the two upstanding end portions, and a wardrobe tray member positioned within the box-like member and connected to the hinged end portion and movable to a vertical position outside of the box-like member and resting on the hinged end portion. 60

2. A wardrobe seat box, comprising a box-like member having an open top and end portions which project above the seat portion of the member, one of said end portions formed of two hinged together parts, a seat cover hinged at one of its side edges 65 portions to the box-like member and movable to closed position between the two upstanding end portions, a wardrobe tray member positioned within the box-like member and connected at one end to and movable with the hinged end portion, said tray member having an open top facing outwardly from the box member when swung to vertical position. 70

75 In testimony whereof, I affix my signature, in presence of two witnesses.

GEORGE HENRY WHEARY.
